BRAUN TUBE FOR PRODUCING TELEVISION IMAGES OF LARGE SIZE

Filed June 11, 1934

Inventor:

Kurt Schlesinger

UNITED STATES PATENT OFFICE

2,111,941

BRAUN TUBE FOR PRODUCING TELEVISION
IMAGES OF LARGE SIZE

Kurt Schlesinger, Berlin, Germany

Application June 11, 1934, Serial No. 730,112
In Germany June 27, 1933

1 Claim. (Cl. 250—27.5)

It is known that in Braun tubes having two pairs of deflecting plates a mutually disturbing action takes place between the pairs of deflecting plates.

5 It has already been proposed by the applicant for the purpose of avoiding these disturbing effects to space the pairs of deflecting plates widely apart, to provide screening means between the pairs of plates, and/or to screen off the leads 10 against each other.

10 The proposed measures, taken singly or in their entirety, have been found to be sufficient so long as the size of image does not appreciably exceed a certain size (approximately 9 x 12 cm. or also

15 10 x 15 cm.).

It has been found, however, that these measures are not fully adequate for the production of television images of large size, and that in the case of large images of this nature the known 20 trapezoid defect is not to be wholly eliminated by reason of the same.

The subject matter of the invention is a Braun tube of large size, for instance more than 9 x 12 cm., having a picture receiving screen, which 25 permits of the production of large images of exactly rectangular form.

According to the invention, the first deflection (for example image deflection) is performed by the use of deflecting coils, and the second deflection (for example line deflection) by the use of 30 deflecting plates.

The use of deflecting coils for the image deflection is possible without difficulty owing to the slow image-change frequency (for example, 25-50 35 periods).

Since the magnetic and the electrostatic fields do not in the present case interfere with each other, it is possible according to the invention to avoid completely the trapezoid defect, and to produce entirely rectangular images of large size.

40 Further, the use of the mixed deflection permits of avoiding the influence of the deflecting field upon the breaking field of the electron-optical system, which otherwise—especially in tubes 45 of the high vacuum type—is very difficult to be avoided.

A tube according to the invention is illustrated by way of example in the drawing. In the same:

50 1 is the bulb, 2 the fluorescent screen, 3 the deflecting coil for the image deflection and 4 the deflecting plates for the line deflection. The distance between the plates 4 and the image screen is made to be such that on the latter there are produced television images of large size (for

example, larger than 10 x 15 cm.). This distance may amount, for example, to 20-30 cm. or more. 5 is an electrode acting as electron return flow interceptor, and 6 a metallic wall coating. The wall coating 6 may conveniently be linked 5 up with anode potential, whilst the ring 5 may possess a potential which is positive in relation to the anode. 7 is the cathode, 8 the control electrode. 9 shows a metallic diaphragm acting as the first anode, said diaphragm being provided 10 with the opening 12 which is focussed on to the picture receiving screen by means of an electron-optical system comprising the electrodes 10 and 11.

Further, means are provided for supplying the 15 deflecting plates with a deflecting voltage of one frequency; and means for supplying the deflecting coils with a deflecting voltage of another frequency. Such means are generally known in the art and are indicated in the drawing by 14, 20 resp. 13.

Means for supplying the metallic coating with the anode potential and means for supplying the auxiliary electrode 5 with a potential, which is higher than the anode potential, are indicated 25 at 15.

The provision of the two auxiliary electrodes 5 and 6 is of particular importance in the case of the Braun tube according to the invention—which is preferably operated under high vacuum—as a rounding off may occur if an auxiliary field of this nature is not provided.

I claim:

In a television cathode ray tube the combination with a picture receiving screen having an 35 area of at least 10 times 15 centimetres, of a picture area scanning system comprising a pair of deflecting plates adapted to be supplied with a deflecting voltage of one frequency for deflecting the cathode ray in one direction and a pair of 40 deflecting coils adapted to be supplied with a deflecting voltage of another frequency for deflecting the cathode ray in another direction vertical to the first said one, of an auxiliary electrode mounted between said scanning system and said 45 screen and adapted to be supplied with a potential lying above anode potential, and of a metallic coating applied to the wall of the cathode ray tube, said coating beginning near said auxiliary electrode and projecting for at least 8 centimetres 50 in the direction towards said screen, said coating being adapted to be supplied with anode potential.

KURT SCHLESINGER.
